SADDLE FOR UNICYCLES

Frank P. Brilando, Niles, and Anton J. Panzica, Hinsdale, Ill., assignors to Schwinn Bicycle Company, Chicago, Ill., a corporation of Illinois

Filed Aug. 24, 1967, Ser. No. 8,382

Term of patent 14 years

(Cl. D90—16)

FIGURE 1 is a top plan view of a saddle for unicycles showing our new design;

FIG. 2 is a side elevation, with a supporting post shown in broken lines;

FIG. 3 is a rear elevation as seen from the left side of FIG. 2; and

FIG. 4 is a detail section taken substantially on the line 4—4 of FIG. 1.

The saddle post, shown fragmentarily and in broken lines in FIGURES 2 and 3, is included only for illustrative purposes.

We claim:

The ornamental design for a saddle for unicycles, as shown and described.
